UNITED STATES PATENT OFFICE.

JAMES H. RANDELS, OF POPLAR BLUFF, MISSOURI.

PUMP.

1,155,370.

Specification of Letters Patent.

Patented Oct. 5, 1915.

Application filed June 11, 1914. Serial No. 844,387.

To all whom it may concern:

Be it known that I, JAMES H. RANDELS, a citizen of the United States, residing at the city of Poplar Bluff, in the county of Butler 5 and State of Missouri, have invented a new and useful Pump, of which the following is a specification.

The present invention relates generally to pumps, and it has particular reference to 10 drainage pumps.

The invention consists generally in an improved screen and agitator device adapted to coöperate with the intake of the drainage pump to prevent the intaking of undesired 15 objects and which only permits the passage of the particles of gravel and sand of the desired dimensions.

An object of the invention is to provide a screen and agitator device, with means for 20 mounting and holding the same in proper position with respect to the intake of the pump, and means for actuating the screen and agitator device to remove from the field of suction such accumulations as may be 25 drawn into engagement with said device, so that said accumulations will be thrown or moved permanently outside of the field of suction, thus leaving the intake open to receive the clean sand and gravel.

30 Another object is to provide a revoluble screen and agitator with means for supporting the same in desired proximity to the open end of the intake of a pump, so that said screen and agitator will prevent the 35 passage of undesired accumulations (other than the clean sand and gravel) into the intake, and means for operating the screen and agitator to remove the accumulations 40 from the field of suction, and also to loosen the gravel or sand and to move the intake from one position to another as may be desired.

Other objects will appear from the following description, reference being made to 45 the accompanying drawing, in which I have illustrated an embodiment of the invention which I have found particularly adapted to the foregoing purposes and in which:—

Figure 1 is a view illustrating the intake 50 of a suction pump having my present invention mounted in coöoperative combination therewith. Fig. 2 is a view looking toward the open end of the intake and the screen and agitator device.

55 The usual rubber hose 1 is connected with the metallic intake pipe 2, it being under-

stood that the hose 1 receives the materials which are drawn into the intake and serves as a passage for delivering the materials to any point of discharge. The intake 2, as 60 usual, is adapted to be placed upon or adjacent to the materials, such as sand or gravel, which are to be pumped.

The screen and agitator device includes a shaft 3 which is journaled in bearings 4 ad- 65 justably secured to the intake. In the embodiment shown, the bearings 4 constitute parts of detachable clamps 5 which are removably secured upon the intake pipe and are held in position by being clamped thereon. The shaft 3 supports the screen and agitator device on its lower end and in the present instance said device comprises a series of arms or spokes 6 radiating from a hub 7 which is mounted upon the lower end 75 of the shaft 3.

A series of rings 8 are secured to the arms or spokes 6 and are concentric with the shaft 3, so that when said shaft is revolved in its bearings, the rings 8 will be moved across 80 the open end of the intake. Thus, any accumulations, such as grasses, or leaves or similar debris, which may be drawn toward the intake by the force of the suction will be caught and prevented from entering the 85 intake by the arms 6 and the rings 8.

It may be desirable, on different occasions, to adjust and support the screen and agitator device in different positions with respect to the open end of the intake pipe. 90 This may be readily effected by means which I have illustrated in Fig. 1, said means including two adjustable collars 9 mounted upon the shaft 3 and provided with clamping devices 10 adapted to engage with said shaft to hold said collars rigidly thereon. Thus, by adjusting one of said collars above one of the bearings 4 and the other of said collars below one of said bearings 4, the shaft 3 will be prevented from longitudinal 100 or axial movement and it may be positioned so as to hold the agitator and screen device at any desired distance from the open end of the intake. By revolving the shaft 3 and thereby the screen and agitator device all accumulations so caught may be conveniently removed from the field of suction, leaving the intake open to receive the clear sand and gravel, without removing the intake from the sand or gravel bed.

105 In the embodiment shown the arms or spokes 6 are of such length that they will ex-

tend into and loosen or agitate the bed of sand or gravel below the intake pipe, thus combining in a single device and operation the double function of screening and removing the undesired accumulations from adjacent to the intake, and also stirring, or agitating or loosening the sand or gravel in the bed thereof. The screen device is also of such size as to prevent the admission of large gravel which will also be carried laterally out of the field of suction by the arms 6.

As a convenient means for manipulating the screen and agitator, I provide a shaft 11 which is connected to the shaft 3 by the universal joint connection 12, the upper end of the shaft 11 being provided with a hand-wheel 13 for manipulative purposes. Thus, by revolving the shaft 3 through the manipulation of the wheel 13, the screen and agitator device may be operated to perform its various functions. The provision of the revoluble device adjacent to the end of the intake dispenses with the need of bars to prevent the taking in of too large bodies of gravel, etc.

In addition to the uses thereof above mentioned, it is apparent that the radial arms or spokes 6 may also be utilized as tractors to move the open end of the intake from one position to another upon the bed of gravel or sand. It will be apparent that there may be various modifications in the construction and arrangement of the screen and agitator, and that it may be applied to various other uses than those particularly mentioned.

I have attempted to describe only one embodiment of the invention and a few of the uses which it is adapted to serve. I do not restrict myself to specific features of construction or arrangement, nor limit myself to any particular uses, but

What I claim and desire to secure by Letters Patent is:—

1. A pump comprising an intake pipe, 45 clamps detachably supported by said pipe, bearings in said clamps above said pipe, a shaft revolubly journaled in said bearings, a series of arms supported by the end of said shaft adjacent to the end of said pipe, adjustable means coöperating with said bearings and said shaft whereby said arms may

be supported at any desired distance from the end of said pipe, and manual means for revolving said shaft.

2. A pump comprising an intake pipe, 55 clamps detachably supported by said pipe, bearings in said clamps above said pipe, a series of radial arms attached to said shaft adjacent to the open end of said pipe, a series of rings of different diameters concentric with said shaft and supported by said arms, adjustable devices coöperating with said bearings and said shaft whereby said arms and said rings may be retained at any desired distance from the open end of said 65 pipe, and manual means for revolving said shaft.

3. A pump comprising an intake pipe, 70 clamps detachably supported by said pipe, bearings in said clamps above said pipe, a series of arms attached to said shaft adjacent to the open end of said pipe, a series of rings of different diameters attached to said arms, adjustable devices coöperating with said bearings to hold said shaft in position 75 to hold said arms and said rings at any desired distance from the end of said pipe, an additional shaft, a universal pivot joint connecting said additional shaft with said first-named shaft, and manual means for revolving said additional shaft and thereby said 80 first-named shaft.

4. A pump comprising an intake pipe, 85 bearings wholly supported by said intake pipe, a shaft journaled in said bearings, arms attached to said shaft adjacent to the open end of said pipe, rings of different diameters attached to said arms, devices coöperating with said bearings to hold said shaft in position to retain said arms and 90 rings at any desired distance from the open end of said pipe, an additional shaft pivoted to said first-named shaft, and means for revolving said additional shaft.

In witness whereof, I have signed this 95 specification in the presence of two subscribing witnesses.

JAMES H. RANDLES.
